UNITED STATES PATENT OFFICE

99,203

DESIGN FOR AN UNDERGARMENT

William B. Malouf, Los Angeles, Calif.

Application October 31, 1934, Serial No. 53,837

Term of patent 14 years

To all whom it may concern:

Be it known that I, William B. Malouf, a citizen of the United States, residing at Los Angeles, in the county of Los Angeles and State of California, have invented a new, original, and ornamental Design for an Undergarment, of which the following is a specification, reference being had to the accompanying drawing, forming part thereof.

I claim:

The ornamental design for an undergarment as shown.

Signed at Los Angeles, in the county of Los Angeles, State of California, this 18th day of October, 1934.

WILLIAM B. MALOUF.
